Primary Examiner — Paula Allen Greene*(74) Attorney, Agent, or Firm* — Kilpatrick Townsend & Stockton LLP(57) **CLAIM**

The ornamental design for headphones, as shown and described.

DESCRIPTION

FIG. 1 is a front, left side perspective view of headphones showing our new design;

FIG. 2 is a front, right side perspective view thereof;

FIG. 3 is a front elevational view thereof;

FIG. 4 is a rear elevational view thereof;

FIG. 5 is a top plan view thereof;

FIG. 6 is a bottom plan view thereof; and

FIG. 7 is a left side elevational view thereof;

FIG. 8 is a right side elevational view thereof;

FIG. 9 is a cross sectional view taken along line 9-9 of FIG. 1; and,

FIG. 10 is a cross sectional view taken along line (10-10) of (the perspective view of) FIG. 2.

The broken lines depict portions of the headphones in which the design is embodied that form no part of the claimed design.
